UNITED STATES PATENT OFFICE

109,721

DESIGN FOR A DRESS

Margaret Michelson, New York, N. Y.

Application February 10, 1938, Serial No. 75,028

Term of patent 3½ years

To all whom it may concern:

Be it known that I, Margaret Michelson, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the specific bust section which is Shirred and draped as shown, in association with the specific skirt flounce.

I claim:

The ornamental design for a dress, substantially as shown and described.

MARGARET MICHELSON.
